UNITED STATES PATENT OFFICE.

FRANÇOIS BAVEREY, OF LYON, FRANCE, ASSIGNOR TO SOCIETE DU CARBURATEUR ZENITH, OF LYON, FRANCE.

CARBURETOR.

Application filed October 23, 1917. Serial No. 198,176.

To all whom it may concern:

Be it known that I, FRANÇOIS BAVEREY, a citizen of the Republic of France, residing at Lyon, No. 67 Boulevard des Belges, 5 France, have invented a new and useful Improvement in Carburetors, of which the following is a full, clear, and exact description, reference being had to the accompanying drawings, forming part of this specification, 10 in which:—

Figures 1, 2, 3 and 4 are diagrams illustrating different embodiments of the invention, and

Figures 5, 6, 7 and 8 are views of a carburetor embodying the invention.

Figure 5 is a view partly in elevation and partly in section along the line V—V of Figure 8. Figure 6 is a vertical section along the lines VI—VI of Figure 8. Figure 7 is 20 a side elevation partially in section. Figure 8 is a plan view partly in section along the line VIII—VIII of Figure 6.

The present invention relates to carburetors and more especially to carburetors for 25 use in aviation.

In an ordinary carburetor consisting of a nozzle which furnishes in the air conduit the gasoline supplied by constant level apparatus, it is possible to decrease the flow 30 of the nozzle by establishing in the constant level chamber a pressure below atmospheric pressure. To cause this reduction in pressure it is sufficient, as shown in Figure 1 of the drawings, to establish a communication 35 through the tube *e* between the constant level chamber and the carburetor air passage at the point *d* between the nozzle and throttle valve and to establish a communication 40 between the same constant level chamber and the outer air through a small orifice *g*. According to the position of the pet cock *r* located in the tube *e*, it is possible to impress upon the float chamber a certain 45 amount of suction which varies from nothing when the pet cock *r* is closed up to a certain fraction of the suction at *d* when the pet cock is open, this fraction being dependent on the ratio of the cross sections of the 50 passages *e* and *g*.

Theoretical considerations show that the reduction in the pressure in the float chamber is in a given ratio with the suction which obtains at the end *j* of the nozzle, this ratio depending, as explained before, on the 55 relative sizes of the passages *e* and *g*. It

will therefore be seen that the flow from the nozzle *j* will be reduced when the communication through the passage *e* is open, and that this reduction will be dependent only on the relative cross sectional areas of the 60 passages *e* and *g*. While the retarding effect of the suction in the float chamber varies with the suction in the manifold, the effect on the nozzle varies also with the suction, but the percentage by which the flow is 65 reduced is independent of the suction within the carbureting chamber as it depends solely on the relative areas of the passages 70 *e* and *g*, as varied by the pet cock *r*. In other words, there is no change in the character of the flow through the nozzle. The flow through the nozzle is the same as it would be if the nozzle *j* had been reduced in diameter. The present invention relates 75 particularly to the application of this principle to carburetors having one or a plurality of sunken jets either alone or combined with the ordinary jets. By sunken jet is meant a jet placed below the normal level of the fuel and delivering fuel into a chamber more or less open to the atmosphere, 80 said fuel being thereafter conducted to the carburetor air passage. A carburetor of this type is shown in the United States patent of François Baverey, Patent No. 907,953, 85 patented December 29, 1908.

The regulation obtained by the present invention is particularly well adapted to aeroplane motors in order to decrease the quantity of gasoline when the specific gravity 90 of the air becomes lessened due to the high altitude.

In Figures 2 and 3 is illustrated diagrammatically the invention as embodied in carburetors having a single sunken jet *i*. In 95 Figure 2 the well *p* of the sunken jet *i* is open directly to the atmosphere while in Figure 3 the air necessary for the operation of the sunken jet *i* is taken from the upper part of the float chamber. It is found that, other things being equal, the decrease in 100 flow, due to the reduction in pressure through the tube *e*, is more pronounced in the construction shown in Figure 2, than in that 105 shown in Figure 3.

In a carburetor having a suction controlled jet *j* and a compensating sunken jet *i*, such as is shown in Figure 4, it is advisable to have the well for the jet *i* communicate with the float chamber. In Figure 4 the opening 110

g, through which the upper part of the float chamber communicates with the atmosphere, is connected through the tube h to the air entrance a of the carburetor, instead of opening directly to the atmosphere, as illustrated in Figures 1, 2 and 3. In this way the pressure at the mouth of the tube h is maintained at the same pressure as the air inlet of the carburetor, as described in the application of Francois Baverey, Serial No. 87,720, filed March 30, 1916. By this means the carburetor and its mode of regulation are rendered independent of the fluctuations of pressure at the opening through which the carburetor takes air from the atmosphere.

A carburetor constructed in accordance with one embodiment of my invention is illustrated in Figures 5 to 8 inclusive. The openings of the two gasoline supply nozzles, indicated generally at small j, are concentric as usual in the art, as illustrated for example in the Baverey Patent No. 907,953, patented December 29, 1908. The well p is formed adjacent to the float chamber c in which the fuel level is maintained constant by means of a float operated valve, as will be readily understood by those skilled in this art without further explanation. The well p communicates with the top of the float chamber through the opening k. The float chamber c indirectly communicates with the atmosphere through the passage g, h which opens into the air intake chamber a of the carburetor.

The float chamber c also communicates with the air passage of the carburetor at a point between the throttle valve m and the nozzle j by means of the passage e. The end of this passage is bored out to form a chamber l and a conical seat o for the valve r. The valve r is hollow and is provided with an opening t adapted to register with the opening d drilled in the body of the carburetor. Valve r is held in contact with its conical seat by means of the spring sp. Hand lever s is mounted on the stem whereby the valve may be rotated to bring the openings t and d into and out of register.

The two jets of the carburetor are so adjusted that a substantially constant ratio between the gasoline and air is maintained for different speeds of the motor according to the well known principle of the Zenith carburetor, as described for example in the Baverey Patent No. 907,953. The operation of the air passages e and g is to decrease the gasoline supply while still permitting the carburetor to maintain a substantially constant gasoline-air ratio for different speeds of the motor. This is of particular importance in carburetors for use with aeroplanes. It has been found that when the aeroplane rises into rarefied atmosphere the mixture furnished by a carburetor becomes richer in

gasoline. The compensation for this tendency, the valve r may be adjusted so as to decrease the pressure in the float chamber and thereby reduce the gasoline supply.

While the preferred embodiment of the invention is described and illustrated, it is to be understood that the present invention is not limited to its illustrated embodiment but may be embodied in other carburetor constructions within the scope of the following claims.

I claim:

1. A carburetor, comprising a carbureting passage, fuel supply means in said passage, a throttle valve therein, a constant level fuel chamber, a sunken jet for supplying fuel from the chamber to one of said supply means in the carbureting passage, a connection from the top of the constant level chamber to the carbureting passage at a point between the fuel supply means and the throttle valve, a connection from the top of the constant level chamber to the atmosphere through the carbureting passage, and means for regulating the connection between the top of the constant level chamber and the carbureting passage, substantially as described. 80

2. In a carburetor, a carbureting passage, a constant level chamber, an auxiliary fuel chamber fed from the constant level chamber through a metering orifice placed below the level of the fuel therein, a fuel connection from the auxiliary chamber to the carbureting passage, an air connection between the air intake of the carburetor and the constant level fuel chamber and an air connection for the top of the auxiliary fuel chamber whereby air may mix with the fuel in the fuel connection to the carbureting passage, and a regulable conduit between the carbureting passage and the float chamber, substantially as described. 95

3. In a carburetor, a carbureting passage, a constant level chamber, an auxiliary fuel chamber fed from the constant level chamber through a metering orifice placed below the level of the fuel therein, a fuel connection from the auxiliary chamber to the carbureting passage, an air connection between the air intake of the carburetor and the constant level fuel chamber to communicate the pressure of the air intake to said float chamber, an air connection for the top of the auxiliary fuel chamber whereby air may mix with the fuel in the fuel connection to the carbureting passage, and adjustable means for modifying the effect produced in the float chamber by the first mentioned air connection, including an air connection from the float chamber to the carbureting passage, substantially as described. 110

4. A carburetor having a float chamber, a carbureting passage, a fuel jet, means to communicate to the float chamber a pressure 120

corresponding to that of the air intake of the carburetor, means to communicate the same pressure to the fuel jet and means to communicate a different pressure to the 5 float chamber to modify the pressure condition maintained by said first recited pressure communicating means, substantially as described.

5. A carburetor having a carbureting passage, a float chamber, a fuel jet, means to communicate to the float chamber a pressure corresponding to that in the air intake of the carburetor, means including an air connection from the float chamber to the carbureting passage for communicating a different pressure to the float chamber to modify the pressure condition communicated by said first recited means, and a manually operable valve in said air connection, substantially as described.

6. In a carburetor, a constant level fuel chamber, a carbureting passage, a suction controlled jet receiving fuel from said chamber, an auxiliary fuel chamber, a sunken jet 25 for supplying fuel from the auxiliary fuel chamber to the carbureting passage, an air connection for the auxiliary fuel chamber, a

connection between the constant level chamber and the carbureting passage, and a third connection from the top of said constant 30 level chamber for modifying the action of said second connection, substantially as described.

7. In a carburetor having a carbureting passage, a float chamber, an auxiliary fuel 35 chamber fed therefrom, a fuel jet supplying fuel from said auxiliary chamber to said carbureting passage, a balancing means to maintain a pressure in the float chamber corresponding to that of the air intake of 40 the carburetor, a pipe connected to the balancing system of the float chamber and leading into said carbureting passage for modifying the action of the balancing system, a 45 regulable means in said pipe, and a second fuel jet fed directly from the float chamber, substantially as described.

In testimony whereof, I have hereunto set my hand.

FRANÇOIS BAVEREY.
